UNITED STATES PATENT OFFICE.

WILLIAM F. DURFEE, OF BRIDGEPORT, CONNECTICUT.

VALVE.

SPECIFICATION forming part of Letters Patent No. 323,404, dated August 4, 1885.

Application filed March 28, 1884. (No model.)

To all whom it may concern:

Be it known that I, WILLIAM F. DURFEE, a citizen of the United States, residing at Bridgeport, in the county of Fairfield and 5 State of Connecticut, have invented certain new and useful Improvements in Valves; and I do hereby declare the following to be a full, clear, and exact description of the invention, such as will enable others skilled in the art to 10 which it appertains to make and use the same.

My invention relates to that class of valves which are especially adapted for use in connection with hydraulic cranes, presses, &c., and has for its object to produce a perfectly-balanced sliding valve which shall be simple in 15 construction, easy to operate, and which will not leak. With these ends in view I have devised the novel construction which I will proceed to describe, referring by letters to the accompanying drawings, forming part of this 20 specification, in which—

Figure 1 is an elevation of the device complete; Fig. 2, a transverse section on the line $x-x$, Fig. 1; Fig. 3, a longitudinal section, with 25 the rack and lever in elevation; and Fig. 4, a view illustrating a modified form of operating mechanism.

Similar letters indicate the same parts in all the figures.

30 A , A' , A^2 , A^3 , and A^4 represent a series of castings, which are held in position by four longitudinal bolts, B .

B' is a flange cast with or secured to casting A^2 , by means of which the valve is held in 35 place by bolts or in any suitable manner. A central longitudinal opening extends through all of these castings, which, in castings A , A^2 , and A^3 , is sufficiently enlarged to form circular chambers a , a^2 , and a^3 , which may be termed, 40 respectively, "discharge," "induction," and "circulating" chambers. Castings A , A^2 , and A^3 are provided at both ends and castings A' and A^4 at their inner ends with concentric recesses b . At the inner edges of these 45 recesses the metal is smoothed away, leaving rounded corners b' .

C are metallic disks, preferably of brass, which also have central openings. These disks are thickest at their central openings, 50 the metal being curved down to a feather edge, c , on both sides of the central disks and on the inner sides of the two end disks. The

disks are circular in form, and are the exact diameter of the recesses in the ends of the castings, so that in assembling the castings are 55 centered by the disks.

Between the disks and the castings I place cup-leathers D , which are closely held between the curved surfaces of the disks and the rounded corners of the castings. 60

E is a tube or cylinder closed at its ends and having circumferential perforations e at two points in its length. This cylinder closely fits the two end castings and the metallic disks, and is adapted to have reciprocatory move- 65 ment therein.

F is the induction-pipe, which communicates with chamber a^2 ; G , the eduction-pipe, which is connected with chamber a^3 ; and H , the circu- 70 lating-pipe, which leads from chamber a to the jack or other apparatus to which it is desired to convey water.

K is a bar which slides in a way or groove, K' , in casting A . This bar is provided upon one side with stops K^1 , which engage the heads of set-screws K^2 , projecting from casting A , to limit the movement of the bar, as shown in Fig. 3. On a portion of its length the bar is provided with rack-teeth K^3 . 75

L is a lever pivoted in bearings L' , which 80 project upward from the casting A . At the lower end of the lever is a sector, L^2 , having teeth L^3 , which engage with rack-teeth K^2 upon the bar to operate the same.

The tube or cylinder E extends through the 85 central openings in the series of castings and the disks C , fitting closely in all of the disks and in the two end castings, A' and A^4 , which are the bearings in which it reciprocates.

When the parts are assembled, the cup-leathers are held between the castings and the disks, and are pressed against the cylinder, thus preventing any appreciable leakage or escape of water from one chamber to another. Should slight leakage occur outward 95 from chambers a or a^3 , by means of water passing between the cup-leather and disk and the tube, this leakage will collect in small chambers M in castings A' and A^4 , from which waste-pipes M' lead. These pipes are connected 100 with the eduction-pipe G , so that escape of water outside of the valve is practically impossible. As an additional precaution against leakage, it will be noticed that the cup-leath-

ers on each side of the disks are of sufficient length to bear for a short distance upon the tube, the ends of said cup-leathers extending outward into the chambers from the point at 5 which they are held between the feather edges of the disks and the rounded corners of the castings, so that the pressure of the water in the chambers is upon the outer surface of the cup-leathers. The greater the pressure of 10 water, therefore, in any of the chambers, the closer the cup-leathers will bind the tube and the less will be the possibility of any water escaping.

N N are upright supports, into which the 15 ends of the tube are screwed, and which rigidly connect the same with bar K by means of bolts N², or in any suitable manner.

N' N' are gaskets against which the ends of the tube bear to secure water-tight joints.

20 The operation is as follows: The water enters chamber a² at all times through pipe F. When the valve is open, as shown in the drawings, the water passes from chamber a² through the right-hand series of perforations 25 e into tube E. The water escapes from the tube through the left-hand series of perforations into chamber a³, and from thence it passes into pipe H, which leads to the jack or other apparatus which it is desired to operate.

30 To stop the flow of water, lever L is lifted to a vertical position. As the lever is lifted the teeth upon the sector engage with those upon bar K, moving the bar, and with it the tube, toward the right. When the lever is in a 35 vertical position, the tube will have been carried toward the right sufficient distance to bring the right-hand series of perforations in contact with the inner face of the disk between chambers a² and a³. In practice I 40 usually make the perforations in two rows extending entirely around the tube. The number and arrangement of these perforations or orifices, however, is a matter of no consequence, except to this extent, that the right-hand series must be within a space longitudinally of 45 the cylinder, which is less than the bearing-face of the disk between chambers a² and a³, so that the perforations may all be covered thereby.

When the parts are in the position just 50 described, no water can pass from the valve into pipe H, nor can any water pass from said pipe into the valve. In use the tube and chamber a are always filled with water, said chamber being made sufficiently long so that 55 at neither extremity of the motion of the tube can the left-hand series of perforations pass outside of it. Water may thus pass into or be received from pipe H at any time, the direction of the flow depending upon the position of the right-hand series of perforations 60 relatively to chambers a² and a³. When lever L is in the vertical position just referred to, there can be no circulation of water. The jack or other apparatus will consequently be 65 held stationary, the parts remaining in the exact position they occupied when the flow of water into pipe H was cut off. To reverse

the flow of water, lever L is moved over to the left to about the corresponding angle of inclination to that shown in Figs. 2 and 3—that 70 is to say, the lever will then stand at the same angle relatively to a perpendicular line drawn through its axis, as is shown in Figs. 2 and 3, but will be at the left of said line, instead of at the right, as shown. This movement, by means 75 of the sector and rack, carries the tube to the right, bringing the right-hand series of perforations into chamber a², into which the water in the tube and pipe H flows, then out through eduction-pipe G.

80 It will be observed that by my improved construction I secure a perfect balance of pressure, no matter what may be the position of the tube relatively to the induction, eduction, or circulating chambers; also, that the movement 85 of the parts is positive and the action instantaneous.

It will of course be obvious that the details of construction may be varied considerably 90 without departing from the spirit of my invention, the gist of which consists in the use of a sliding tube having two sets of perforations, one of which remains constantly within the limits of the circulating-chamber, the other set being adapted to be moved into the induction or the eduction chambers or placed contiguous to the inner face of the metallic disk which separates said chambers.

95 The operating mechanism shown is not an essential feature of my invention, but will be 100 found preferable for many uses. Instead of the sector and rack, however, movement may readily be imparted to tube E by means of a quick-acting screw having bearing in a separate casting; or, as shown in Fig. 4, casting A⁴ 105 may be prolonged into an outwardly curved arm, A⁵, to which the lever may be pivoted. In this construction no rack and sector are used, and instead of being screwed into a support, 110 N, the tube is provided with a slotted head, N³, within which the lever is pivoted, the end 115 of the lever being also slotted, as shown, to permit free movement on the pivot.

Having thus described my invention, I 120 claim—

1. In a valve, the combination of a plurality of annular sections, A A² A³, the ducts F G H, a sliding tube of less diameter than the interior of said sections and having the apertures 125 e, and the disks C and their packings clamped between the ends of said sections and forming bearings for the sliding tube, and partitions for dividing the annular space between the tube and said sections into chambers, substantially as set forth.

2. In a valve, the combination of a watertight casing having ducts communicating therewith, a tube adapted to slide therein and place the desired ducts in communication with one another, said tube being connected with a 130 parallel bar, also adapted to slide in the casing, whereby the alignment of the tube is maintained, substantially as set forth.

3. In a valve, the combination of a water-

tight casing having ducts communicating therewith, and a tube adapted to slide therein and place the desired ducts in communication with one another, said tube being connected 5 with a parallel bar, also adapted to slide in the casing, the bar being provided with a rack, and the casing with a lever and segment for actuating the rack and tube, substantially as set forth.

10 4. In a valve, the combination of a plurality of annular sections, A A² A³, the ducts F G H, a sliding tube of less diameter than the interior of said sections and having the apertures e, and the disks C and their packings clamped 15 between the ends of said sections and forming bearings for the sliding tube, and partitions for dividing the annular space between the tube

and said sections into chambers, said sections having in their ends the recesses b, adapted to receive and fit the disks C, thereby centering 20 the sections, substantially as set forth.

5. The casting A, having a groove, K', and set-screws K¹, the bar K, having a rack, and stops K², in combination with a toothed sector which engages the rack, supports N, which 25 connect the rack with the perforated sliding tube, and induction, eduction, and circulating chambers, through which the tube passes.

In testimony whereof I affix my signature in presence of two witnesses.

WILLIAM F. DURFEE.
